AEROSLEIGH

Milford Geary, P.O. Box 26, Polo, Ill. 61064
Filed Feb. 11, 1970, Ser. No. 21,399

Term of patent 14 years

Int. Cl. D12—07

U.S. Cl. D71—1

FIG. 1 is a perspective view of the aerosleigh of this invention;

FIG. 2 is a side elevational view;

FIG. 3 is a plan view;

FIG. 4 is a front elevation view with the landing gear retracted.

I claim:

The ornamental design for an aerosleigh, substantially as shown and described.
